UNITED STATES PATENT OFFICE.

HYLA FREDERICK MAYNES, OF GAINES, PENNSYLVANIA, ASSIGNOR OF ONE-HALF TO
EMMA C. MAYNES, OF GAINES, PENNSYLVANIA.

AMUSEMENT RIDE.

Application filed May 11, 1922. Serial No. 559,986.

To all whom it may concern:

Be it known that I, HYLA F. MAYNES, a citizen of the United States, residing at Gaines, in the county of Tioga, State of Pennsylvania, have invented certain new and useful Improvements in Amusement Rides; and I do hereby declare the following to be a full, clear, and exact description of the invention, such as will enable others skilled in the art to which it appertains to make and use the same.

This invention relates to amusement apparatus of the type in which the amusement is that afforded by a ride of some kind. Merry-go-rounds, roller coasters and scenic railways are examples. Two elements combine to make these devices attractive to the public,—speed and novelty. The old-fashioned roller coaster thrilled with its speed alone. The merry-go-round and scenic railway combine speed, or at least motion, with novel features of various kinds. One of the objects of the present invention is to add something new to an amusement ride. This new thing is a canopy, carried by the cars, which may, during the ride, alternately be opened up to expose to view the passengers in the cars, and closed upon the cars and their passengers, so that they are completely shut off from view of spectators, and made to feel that they are traveling within a tunnel, thus affording a new and unexpected element or incident in the ride. This canopy may be continuous, enclosing the entire train, or each individual car may be separately enclosed. The passengers are not warned as to when the canopy is to be closed, nor when it is to be opened. This adds excitement. Besides, when the canopy is down and the cars are traveling in semi-darkness many things may happen. Sudden blasts of air may blow into the cars and strike the passengers in the face. Strange lights may flicker on the canopy walls. Thus the canopy not only imparts an amusing variety to a ride otherwise without novel interest, but it also affords opportunity for introducing and making more effective other elements of surprise and variety heretofore known to the art.

In an amusement apparatus of this type, it is important that the seating capacity of the

cars should be as large as possible. To avoid decreasing the carrying capacity of such a ride, it is necessary that the enclosing canopy should be so constructed and located that in its folded position it is out of the way of the passengers entering the car. The arrangement of the invention is therefore such that the enclosing canopy when folded lies on the side of the cars away from the loading platform. In the specific embodiment here disclosed, that means that the folded canopy lies between the cars and the center of the merry-go-round, and the canopy is arranged to unfold radially outward, so that as it unfolds its outer edge moves in an arc which rises over and terminates on the outside of the cars, so that when unfolded the canopy conceals the cars and the passengers from the view of the spectators.

In the accompanying drawings I have shown one embodiment of my invention. Certain of the structural features shown are important and are claimed, but the invention in its broader aspects is more than these. In these drawings Fig. 1 is a plan view of the device showing a number of the cars and the canopy in its folded or open position; Fig. 2 is an elevation of the device showing the canopy closed and covering the cars; Fig. 3 is a vertical section on an enlarged scale through a car and the hub of the merry-go-round, the canopy being in its closed position; Fig. 4 is a detail showing in vertical transverse section the canopy in folded position and the supports and guides by means of which it is operated; Fig. 5 is a view similar to Fig. 4, but showing the canopy in closed position; Fig. 6 is a detail plan showing one of the cars and the canopy in its folded position; Fig. 7 is a vertical longitudinal section through one of the cars and the canopy in its closed position over the car and showing the springs by means of which the canopy is automatically returned to its folded position.

The amusement apparatus shown in these drawings is of the merry-go-round type and comprises a central hub 1 which rotates about a vertical hollow shaft 2 and is supported upon suitable bearings 3. Extending outwardly from this hub are a series of radial arms 4 pivoted at 5 to the hub and

supported at their outer ends by wheels 6 which run upon a circular and undulating trackway 7. The outer ends of the radial arms 4 are connected by means of links 8 which permit the device to follow the undulations of the trackway. Mounted upon these links are passenger-carrying cars or carriages 9. Power is supplied to the merry-go-round from a motor 11 which drives a cable 12 encircling a large sheave 13 bolted to and integral with the hub 1. This sheave is supported and steadied by guys 14, fastened to its spokes 15, the upper ones extending from a standard 16 mounted upon the hub. In order to permit the radial arms to rise and fall with the undulations of the trackway it is, of course, necessary that they be pivoted to the hub, but it is obvious that were the rotating power applied at this point a very severe strain upon these pivots would result. It is, therefore, desirable to apply the power at a point somewhat nearer the cars themselves. I therefore provide each arm 4 with flexible connections 17 which extend from a point adjacent each car to one of the spokes 15 of the sheave 13 just ahead, and a similar flexible connection 18 to one of the following spokes. By this means the arms and the cars can follow the undulations of the trackway and yet at the same time the force moving them be positively applied at a point which practically coincides with the weight carried by them and relieves the pivots 5 from strain.

35 In accordance with this invention I have provided a canopy 20, usually of canvas, which covers the entire train of cars and folds radially of the merry go-round. The canopy is normally in open or folded position and rests upon the radial arms on the inside of the seats, as is best shown in Figs. 1, 4 and 6. The canopy is supported when in its closed position by a series of supports 21, which open and close fan-like. These supports are U-shaped, the canopy being secured to them at their closed ends, their open ends being journaled about rods 22, one of which extends from the back of each car 9 and is supported at its other end upon a V-shaped standard 23 carried by the links 8. Each set of supports 21 is extended to close the canopy by means of a cable 24 actuated by means situated at the center of the merry-go-round, as will be described later. The effective component of the pull exerted by this cable is, of course, the one normal to the first support 21, and in order to maintain the angle which this cable makes with this support as nearly 90° as is feasible throughout the entire closing movement, I have provided two guide arms 25 likewise journaled upon rod 22 and provided at their outer ends with eyes 26 through which the cable 24 passes. When the canopy is in its open position, as shown in Fig. 4, cable 24 passes from the uppermost support 21, through the eyes 26 of the guide arms 25, around a pulley 27 mounted within a hanger 28 on one of the outer links and inwardly to the source of power. When pull is exerted upon the cable to close the canopy the arms 25 and the supports 21 swing counter-clockwise (as shown in Fig. 4) about the rod 22 until they assume the position shown in Fig. 5.

The cables 24 from each set of supports 21 extend inwardly, under pulleys 29, and unite at 30 into a common cable. This cable passes about a drum 32 mounted upon the standard 16 and driven by a motor 33. The current for this motor is led to it through a pair of slip rings 34, mounted upon the hollow shaft 2, and brushes 35.

The canopy is returned to its folded position by means of a series of tension springs 36 which extend between the supports 21 of adjacent sets, as shown most clearly in Fig. 7. Now it will be clear from an inspection of Fig. 6 that when the canopy is closed these springs are placed under tension, as the distance between the closed ends of the U supports 21 is greater when the canopy is closed than when it is open, this following from the circular shape of the merry-go-round. Therefore, the moment the tension on cables 24 is relaxed, these springs 36 will automatically return the canopy to its open position. This opening movement is limited by stops 37 upon which the supports 21 ultimately rest. The arms 25 follow the supports 21 to their initial position through the action of flexible connections 38.

When the canopy is closed the cars are completely covered by it. There is, of course, no relative movement between the cars and the canopy, but in the semi-darkness which ensues it is possible to move lights over the outer surface of the canopy, which will give the effect of relative movement and make it appear to the occupants of the cars that they are in fact traveling within a tunnel. However, this is but one of the aspects of the invention. As a matter of fact, each car may be separately cut off from each other car by means of a canvas partition 39 secured to each set of supports 21 and shown in Fig. 5. The cars are also shown provided with slotted bottoms 40 and dashboards 41, so that, if desired, blasts of air may be suddenly introduced to add to the fun of the ride.

I claim:

1. In an amusement ride having a traveling passenger car or train, the combination with the car or train of a canopy traveling therewith and adapted to be interposed between the car or train and spectators, and means for moving the canopy during the ride into and out of concealing position to

- alternately expose and conceal the passengers from the view of the spectators.
2. In an amusement ride having a traveling passenger car or train, the combination with the car or train of a folding canopy traveling therewith and adapted to fold and unfold transversely of the path of movement of the car or train, and means for folding and unfolding the canopy during the ride to alternately conceal the passengers from and expose them to the view of spectators.
3. In an amusement ride having a traveling passenger car or train and a loading platform, the combination with the car or train of a folding canopy traveling therewith and adapted to fold and unfold transversely of the path of movement of the car or train and lying when folded on the side of the car or train away from the loading platform, and means for folding and unfolding the canopy during the ride to alternately conceal the passengers from and expose them to the view of spectators.
4. In an amusement ride having a traveling passenger train, the combination with the train of a canopy traveling therewith and adapted to be interposed between the train and spectators, and means for moving the canopy during the ride into and out of concealing position to alternately expose and conceal the passengers from the view of the spectators, said canopy having partitions arranged to separate at least one car of the train from those adjoining it.
5. In an amusement ride having a traveling passenger train, the combination with the train of a folding canopy traveling therewith and being when folded at one side of the path of movement of the train, and means for folding and unfolding the canopy transversely during the ride to alternately conceal the passengers from and expose them to view of spectators, said canopy having partitions arranged to separate at least one car of the train from those adjoining it.
6. In an amusement ride having a traveling passenger train and a loading platform, the combination with the train of a folding canopy traveling therewith and lying when folded on the side of the train away from the loading platform, and means for folding and unfolding the canopy transversely of the path of movement of the train during the ride to alternately conceal the passengers from and expose them to the view of spectators, said canopy having partitions arranged to separate at least one car of the train from those adjoining it.
7. In an amusement ride, having a traveling passenger car or train, the combination with the car or train of a folding canopy normally lying in folded condition lengthwise of the car or train and to one side thereof, fan-like supports for the canopy pivoted on the car or train, and means for opening out these supports fan-wise to spread the canopy over the car or train.
8. In an amusement ride having a traveling passenger car or train, the combination with the car or train of a folding canopy normally lying in folded condition lengthwise of the car or train and to one side thereof, fan-like supports for the canopy pivoted on the car or train, a cable fastened to each set of fan-like supports through which force is exerted to open them and spread the canopy, and pivoted guide arms for the cable during the opening movement, holding it so that the force exerted by it shall be substantially normal to the moving support.
9. An amusement apparatus of the merry-go-round type, comprising the combination of cars revolving about a central pivot, and a radially folding canopy normally lying in folded condition between the cars and the pivot and adapted to be interposed between the car or train and spectators, and means for moving the canopy during the ride into and out of concealing position to alternately expose and conceal the passengers from the view of the spectators.
10. An amusement apparatus of the merry-go-round type, comprising the combination of cars revolving about a central pivot, a radially folding canopy normally lying in folded condition between the cars and the pivot and adapted to be interposed between the car or train and spectators, and means for unfolding the canopy outwardly during the ride to cover the cars to conceal the passengers from the view of the spectators.
11. An amusement apparatus of the merry-go-round type, comprising the combination of cars revolving about a central pivot, a radially folding canopy normally lying in folded condition between the cars and the pivot, fan-like supports for the canopy pivoted adjacent the cars, tension springs connecting adjacent fan-like supports, means for opening out the fan-like supports to spread the canopy and enclose the cars, the springs serving to return the canopy to its folded position as soon as the opening means cease to act.
12. An amusement apparatus of the merry-go-round type, comprising the combination of cars revolving about a central pivot, a radially folding canopy normally lying in folded condition between the cars and the pivot, fan-like supports for the canopy pivoted on the cars, a cable fastened to each set of fan-like supports through which force is exerted to open them and spread the canopy, and a spring serving to return the canopy to its folded position as soon as the force exerted by the cables is relaxed.
13. An amusement apparatus of the

45
merry-go-round type, comprising the combination of cars revolving about a central pivot, a folding canopy normally lying in folded condition between the cars and the pivot, fan-like supports for the canopy pivoted adjacent to the cars, a cable fastened to each set of fan-like supports through

which force is exerted during the ride to open them and spread the canopy to conceal the passengers from the spectators, and centrally located means for actuating the cables. 10

In testimony whereof I affix my signature.

HYLA FREDERICK MAYNES.
